EXCAVATING AND LOAD HANDLING
APPARATUS
William D. Symank, Genas Isere, France
(24 Rue Bavolet, Lyon, France)
Filed Aug. 2, 1963, Ser. No. 299,507
14 Claims. (Cl. 214—138)

This invention relates to an apparatus for excavating and load handling and more specifically to such an apparatus which is convertible to provide alternative modes of tool operation.

In general, although structural details vary widely, apparatus for excavating or load handling basically comprises a support structure, on which the operator is usually located, a boom pivotally attached at one end to the support structure, and a dipper stick pivotally attached at one end to the end of the boom. Hydraulic actuators swing the boom and dipper stick about their pivotal connections to the support structure and boom end, respectively. A tool of some sort is attached to the bottom end of the dipper stick. The term tool, as used here, refers to any device used for loading handling, or to any implement, such as a bucket or a blade, used for earth moving.

This invention deals specifically with configurations of the apparatus elements which result in desirable patterns of tool motion. Assuming for purposes of illustration that the tool is an excavating bucket, there are excavators in which, except for a bucket-dumping capability, the bucket remains fixed with respect to the dipper stick during the digging stroke, thus causing the bucket to swing in an arc, with the angle which the bucket face makes with a horizontal plane constantly changing. There are also in existence excavators which provide a bucket stroke in which the bucket moves in a substantially horizontal direction, with the bucket face maintaining a constant angle with respect to a horizontal plane. The latter type of motion is desirable, for instance, in forming the flat bottom of a ditch or swimming pool. It would be extremely useful to have a single piece of equipment which incorporated the two types of tool movement discussed.

It is accordingly an object of this invention to provide an excavating and load handling apparatus which may be converted from a mode of tool motion in which the tool moves in an arcuate pattern to a mode of tool motion in which the tool moves in a horizontal line and maintains a constant attitude with respect to a horizontal plane, or vice versa.

It is a further object of this invention to provide such an apparatus in which the conversion may be made quickly and easily, and without the necessity of excessive dismantling and reassembly of the apparatus elements.

It is another object of this invention to provide such an apparatus in which the tool and other elements of the apparatus do not have to be supported during the conversion.

These objectives are achieved, broadly, by pivotally attaching the tool at spaced points to one end of the dipper stick and to one end of a tool linkage. The other end of the tool linkage may be alternatively connected either to the dipper stick, for arcuate tool motion, or to the boom, for a horizontal, constant-attitude stroke. The connection of the tool linkage may be easily changed. When it is connected to the dipper stick, the apparatus elements may be so positioned that the tool linkage may be connected to the boom before being disconnected from the dipper stick. Conversely, for the change from boom to dipper stick connection.

The invention may be more clearly understood by reference to the following detailed description of a pre-

ferred embodiment of this invention in an excavator with a bucket used as the tool, taken in conjunction with the drawings, which form a part of the specification, and in which:

5 FIG. 1 is a side elevational view of a portion of an excavating apparatus embodying this invention, with the tool linkage being connected at one end to the dipper stick structure, providing the apparatus with that mode of operation in which the bucket face swings in an arc with respect to the horizontal plane during the digging stroke;

10 FIG. 2 is a side elevational view of a portion of the excavating apparatus of FIG. 1, with the vehicle base turned 90 degrees, and with the elements of the apparatus being arranged in position to make the conversion from one mode of bucket movement to the other;

15 FIG. 3 is an enlarged view taken along line 3—3 of FIG. 2; and

20 FIG. 4 is a side elevational view of the excavating apparatus similar to that shown in FIG. 2, but with the tool linkage being connected at one end to the boom structure, providing that mode of operation in which the bucket maintains a constant attitude with respect to a horizontal plane and moves along a horizontal line.

25 Turning now to FIG. 1, there is illustrated an embodiment of this invention in an excavating apparatus having a support structure 10 which is mounted upon a vehicle equipped with tractor treads 12 and is rotatable about a vertical axis by means of a turntable 11. A portion of a compressor 13 is shown attached to support structure 10.

30 One end of an angled bottom structure 14 is pivotally connected at 15 to support structure 10. At its other end, boom structure 14 is pivotally connected at 16 to the upper end of dipper stick structure 17. The lower end of dipper stick structure 17 is pivotally connected at 18 to bucket 19. A double-acting hydraulic boom actuator 22 is pivotally connected to support structure 10 at 23 and to boom structure 14 at 24. Two additional bores 29 and 30, located in the middle of boom 14, provide alternative points of pivotal attachment for the upper end of boom actuator 22, providing the equipment with three separate ranges of boom movement. A double-acting hydraulic dipper stick actuator 25 is pivotally connected at 26 to boom structure 14 and at 27 to the two rearwardly extending ears 28 (only one of which is visible in FIG. 1) which form a part of dipper stick structure 17.

35 The tool linkage comprises a double-active hydraulic tool actuator 31 and a tool arm 37, which are pivotally connected to each other at pivot point 34. The other 40 end of tool actuator 31 is pivotally connected at 32 to two forwardly extending ears 33 which form part of dipper stick structure 17. The nature of the attachment of ears 33 to tool actuator 31 may be seen more clearly in FIG. 3. The other end of tool arm 37 is pivotally 45 attached to bucket 19 at pivot point 38, which may be seen to be spaced from pivot point 18, where dipper stick structure 17 is connected to bucket 19. One end of a cross arm 35 is pivotally attached at 34 to the joined ends of tool actuator 31 and tool arm 37, and the other end of cross arm 35 is pivotally attached to dipper stick structure 17 at pivot point 36.

50 A portion of tool actuator 31 extends upwards beyond pivot point 32 and contains a bore 41 which is unused in this configuration. Two boom ears 42, both of which 55 are visible in FIG. 3, form part of boom structure 14 and each of ears 42 contains a bore 43. Bores 43 are coaxial and are unused in the configuration of FIG. 1.

55 Double-acting hydraulic actuators 22, 25 and 31 are connected to compressor 13 through operator manipulated controls and hydraulic lines, all of which are conventional and none of which are shown on the drawings,

for purposes of simplicity. The actuators are independently operable.

The normal digging stroke with the apparatus shown in FIG. 1 is made by extending dipper stick actuator 25 so that dipper stick structure 17 and bucket 19 move through an arc from the solid line position into the dotted line position or beyond. Since the tool actuator 31 is normally operated only at the end of a stroke, to pull the bucket up and prevent spillage while moving the boom, or to swing the bucket down and dump the contents, the bucket will remain fixed with respect to dipper stick structure 17 during the normal digging stroke and therefore will swing in the arc shown, with its face 44 changing in attitude with respect to a horizontal plane or to ground 45. The purpose of breaking the tool linkage into two articulated, pivotally connected parts, tool actuator 31 and tool arm 37, and of providing the additional, pivotally connected cross arm 35, is to permit more efficient dumping of bucket 19. The arrangement shown turns bucket 19 through a much greater clockwise arc about pivot point 18 when tool actuator 31 is extended, than would be the case if the lower end of tool actuator 31 were directly connected to bucket 19.

Turning now to FIG. 2, support structure 10 is shown rotated 90 degrees on turntable 11 from its position in FIG. 1 so that the tractor treads 12 are viewed end on and the vehicle 46 to which treads 12 are attached may be seen. The excavator elements have been arranged to permit conversion from the type of operation shown in FIG. 1, in which the bucket swings in an arc, to the type of operation shown in FIG. 4, in which the bucket moves essentially parallel to a horizontal plane or to the surface 45 of the earth. Dipper stick actuator 25 is fully extended and tool actuator 31 fully retracted, resulting in the alignment of bore 41 at the end of tool actuator 31 with bores 43 at the end of boom ears 42. The fact that this bore alignment which is required for transition is achieved by full extension of one independently operable cylinder and the full retraction of another independently operable cylinder provides great convenience to the operator, in that he is able to achieve accurate bore alignment from his position on the equipment, without the necessity of close personal observation of the cooperating parts and without the necessity of painfully "inching" the parts into their correct relationship.

The relationship of the various bores to each other and the nature of the connections made and unmade in this transition may be seen more clearly in the enlarged view of FIG. 3. When bores 41 and 43 are axially aligned by full extension of dipper stick actuator 25 and full retraction of tool actuator 31, a pin 51 having an enlarged head 52 at one end is driven through bores 41 and 43 and may be secured from withdrawal by means of a cotter pin 53 or the like. This connects tool actuator 31 to boom ears 42 of boom structure 14 in addition to ears 33 of dipper stick structure 17, as shown in FIGS. 2 and 3. All that remains to complete the transition is to remove pin 54 which still remains inserted through bores 56 in ears 33 and bore 55 in tool actuator 31, and therefore still connects the tool actuator to the dipper stick structure. Pin 54 is similar to pin 51 already described, having an enlarged head 57 at one end and being retained against withdrawal at the other end by a cotter pin 58 or the like. Once cotter pin 58 is removed and pin 54 withdrawn, tool actuator 31 is disconnected from the dipper stick structure, resulting in the appropriate configuration for the apparatus to describe the generally horizontal tool movement shown in FIG. 4.

It will be apparent that one of the advantages of this invention is that it permits the tool linkage to be connected to the boom structure while it is still connected to the dipper stick structure. The entire assembly of linkages and attached tool is thus supported by the pivotal connections at 32 while the connection to boom ears 42 is being made,

and there is no necessity for these heavy parts to be supported by the operator during the transition.

FIG. 4 shows a ground-scraping movement in which bucket 19 is moved along the surface 45 of the ground from the solid line position on the left to the dotted line position on the right, while the bucket face 44 is maintained at a substantially constant angle with respect to the ground surface 45.

Note that in the configuration of FIG. 1, if the length of tool actuator 31 remains constant during a digging stroke, which it normally does, the tool will have no freedom of motion with respect to the dipper stick structure, being essentially rigidly attached to it. In the configuration of FIG. 4, on the other hand, this is not so, and the tool is free to move with respect to the dipper stick structure. In FIG. 4, the distance between the two points of pivotal attachment of the tool, that is, the distance between pivotal connection points 18 and 38 on bucket 19, forms one side of a rough parallelogram. The opposite side of this parallelogram is formed by the distance between the pivotal connections of the dipper stick structure and the tool actuator on the boom structure, or between pivotal points 16 and 41, 43 on boom structure 14. The other two sides of the rough parallelogram are dipper stick structure 17 and the tool linkage, which comprises tool actuator 31 and tool arm 37 to which it is connected. While this is far from being a true parallelogram because the tool linkage side is broken into two articulated sections and because of the addition of the pivoted cross arm 35, still it does function roughly as a parallelogram, maintaining its opposed sides parallel no matter how the sides are pivoted about the vertices. Thus as dipper stick structure 17 is pivoted about point 16 by actuator 25, bucket 19 will tend to maintain a constant attitude with respect to boom structure 14; and if boom structure 14 remains stationary and at the appropriate angle, the face 44 of bucket 19 may be maintained at a desired angle with respect to the ground surface 45.

There is a modification to this parallelogram motion, however. As dipper stick structure 17 is swung about pivot point 16, bucket 19 tends to ride upwards, away from ground surface 45. For this reason, boom structure 14 must be lowered during the stroke (see the dotted line position in FIG. 4) to maintain bucket 19 in a horizontal path. This clockwise motion of boom structure 14 about pivot point 15 will tend to alter the attitude of bucket 19 by causing it to turn in a clockwise direction with respect to the ground surface 45. To compensate for this, and maintain the bucket attitude constant with respect to the ground, the parallelogram configuration is deliberately distorted from that of a true parallelogram by making the top side, the distance along the boom structure between pivot points 16 and 41, 43, smaller than the bottom side, the distance along the top of bucket 19 between pivot points 18 and 38. Thus, bucket 19 does not form one side of a true parallelogram, and will not remain precisely parallel to its opposite side as the configuration of the rough parallelogram is changed. Rather, as dipper stick actuator 25 is extended, swinging dipper stick structure 17 counterclockwise about its pivotal connection 16 with boom structure 14, the deviation from a true parallelogram will cause bucket 19 to turn slightly counterclockwise with respect to boom structure 14. This offsets the opposite effect on the attitude of bucket 19 caused by the lowering of boom 14, so that in the combined ground-scraping operation, wherein dipper stick actuator 25 is extended and boom actuator 22 is retracted to lower boom structure 14, the total effect upon bucket 19 will be to move it as shown in FIG. 4, from the solid line position to the dotted line position along a horizontal line, maintaining its face 44 at a constant attitude with respect to the ground 45.

It should be noted in FIG. 3 that the distance between the inner surfaces of ears 33 which project forwardly from dipper stick structure 17 is made greater than the

largest dimension of tool cylinder 31 in that direction so that the tool actuator is free to pass between ears 33 as shown in the solid line position of FIG. 4.

The excavating apparatus of this embodiment is easily convertible from the horizontal tool movement configuration shown in FIG. 4 to the arcuate tool movement configuration shown in FIG. 1. This is accomplished by fully extending dipper stick actuator 25, and fully retracting tool actuator 31 to achieve the physical configuration shown in FIGS. 2 and 3. The conversion is then made by reversing the process for conversion from arcuate tool motion to horizontal tool motion. In making the conversion from the horizontal motion configuration to the arcuate configuration, once bore 55 in tool actuator 31 has been aligned with bores 56 on ears 33 which project forwardly from dipper stick structure 17, pin 54 is inserted through those bores and pin 51 subsequently withdrawn from bores 41 and 43.

While the preferred embodiment of the invention has been described, various modifications may be made while remaining within the scope of the invention, some of which are indicated below.

While hydraulic cylinders are used herein for power actuators 22, 25 and 31, any other power device may be used which is capable of rotating the corresponding elements.

The tool linkage may be a single member, rather than the two pivoted, articulated members used in the preferred embodiment. In fact, depending upon the nature of the tool to be used, the tool linkage need not, for purposes of this inventive concept, be of adjustable length at all. It is conceivable that it be a single, rigid member of constant length, capable of being connected at its upper end either to the boom structure or to the dipper stick structure.

It is not necessary that the proper alignment of the bores for transition from one mode of operation to the other require the full extension of the actuator for the dipper stick structure and the full retraction of the tool actuator. The apparatus may be adjusted so that the proper bore alignment results from any predetermined settings of the appropriate elements.

Other alterations and modifications of the preferred embodiment as may suggest themselves to those skilled in the art are within the scope of the invention, which is defined only by the claims.

What is claimed is:

1. An excavating apparatus comprising the combination of:
  - support means;
  - a boom structure pivotally mounted upon said support means for motion about a first horizontal axis;
  - first power means operatively attached to said boom structure to swing said boom structure about said first horizontal axis;
  - a dipper stick structure pivotally mounted upon said boom structure for motion about a second horizontal axis;
  - second power means operatively attached to said dipper stick structure to swing said dipper stick structure about said second horizontal axis;
  - a tool structure pivotally mounted upon said dipper stick structure for motion about a third horizontal axis;
  - a linkage having two ends, one of said ends of said linkage being pivotally connected to said tool structure at a point spaced from said third horizontal axis,
  - first pivotal attaching means for pivotally attaching the other of said ends of said linkage to said dipper stick structure, and
  - second pivotal attaching means for alternatively pivotally attaching said other of said ends of said linkage to said boom structure at a point spaced from said second horizontal axis,

whereby, by said alternative attaching means there is made available two alternative patterns of tool structure motion when said dipper stick structure is swung about said second horizontal axis.

2. An excavating apparatus comprising the combination of:

support means;

- a boom structure pivotally mounted upon said support means for motion about a first horizontal axis;
- first power means operatively attached to said boom structure to swing said boom structure about said first horizontal axis;
- a dipper stick structure pivotally mounted upon said boom structure for motion about a second horizontal axis;
- second power means operatively attached to said dipper stick structure to swing said dipper stick structure about said second horizontal axis;
- a tool structure pivotally mounted upon said dipper stick structure for motion about a third horizontal axis;
- a power operated linkage of adjustable length, having two ends, and being adapted to swing said tool structure about said third horizontal axis as a result of alteration in its length,
- one of said ends of said linkage being pivotally connected to said tool structure at a point spaced from said third horizontal axis,
- first pivotal attaching means for pivotally attaching the other of said ends of said linkage to said dipper stick structure, and
- second pivotal attaching means for alternatively pivotally attaching said other of said ends of said linkage to said boom structure at a point spaced from said second horizontal axis,

whereby, by said alternative attaching means there is made available two alternative patterns of tool structure motion when said dipper stick structure is swung about said second horizontal axis.

3. An excavating apparatus comprising the combination of:

support means;

- a boom structure pivotally mounted upon said support means for motion about a first horizontal axis;
- first power means operatively attached to said boom structure to swing said boom structure about said first horizontal axis;
- a dipper stick structure pivotally mounted upon said boom structure for motion about a second horizontal axis;
- second power means operatively attached to said dipper stick structure to swing said dipper stick structure about said second horizontal axis;
- a tool structure pivotally mounted upon said dipper stick structure for motion about a third horizontal axis;
- a linkage having two ends,

one of said ends of said linkage being pivotally connected to said tool structure at a point spaced from said third horizontal axis,

said linkage being provided with first and second pivotal connecting elements adjacent the other of said ends;

said boom structure being provided with a third pivotal connecting elements spaced from said second horizontal axis;

said dipper stick structure being provided with a fourth pivotal connecting element;

said first and fourth pivotal connecting elements being operatively engaged, whereby said other end of said linkage is pivotally connected to said dipper stick structure;

said boom structure, said dipper stick structure,

- and said linkage being adapted to be so disposed with respect to each other that said second and third pivotal connecting elements may be operatively engaged and said first and third pivotal connecting elements subsequently disengaged from each other, whereby said other end of said linkage is pivotally connected to said boom structure and disconnected from said dipper stick structure.
4. The apparatus of claim 3 in which said linkage comprises a power operated linkage of adjustable length, being adapted to swing said tool structure about said third horizontal axis as a result of alteration in its length; 10
said second power means comprises a power operated actuating arm of adjustable length; and wherein the disposition of said boom structure, said dipper stick structure, and said linkage with respect to each other so that said second and third pivotal connecting elements may be operatively engaged is accomplished by the adjustment of said linkage and said second power means to predetermined lengths.
5. The apparatus of claim 4 in which said linkage and said second power means both comprise double-acting hydraulic cylinders; 20
said predetermined length of said linkage comprises its shortest length with its hydraulic cylinder fully retracted; and
said predetermined length of said second power means comprises its longest length with its hydraulic cylinder fully extended.
6. An excavating apparatus comprising the combination of:
support means;
a boom structure pivotally mounted upon said support means for motion about a first horizontal axis; 35
first power means operatively attached to said boom structure to swing said boom structure about said first horizontal axis;
a dipper stick structure pivotally mounted upon said boom structure for motion about a second horizontal axis;
second power means operatively attached to said dipper stick structure to swing said dipper stick structure about said second horizontal axis; 40
a tool structure pivotally mounted upon said dipper stick structure for motion about a third horizontal axis;
a linkage having two ends, 45
one of said ends of said linkage being pivotally connected to said tool structure at a point spaced from said third horizontal axis,
said linkage being provided with first and second pivotal connecting elements adjacent the other of said ends; 50
said boom structure being provided with a third pivotal connecting elements spaced from said second horizontal axis;
said dipper stick structure being provided with a fourth pivotal connecting element; 55
said second and third pivotal connecting elements being operatively engaged, whereby said other end of said linkage is pivotally connected to said boom structure;
said boom structure, said dipper stick structure, and said linkage being adapted to be so disposed with respect to each other that said first and fourth pivotal connecting elements may be operatively engaged and said first and third pivotal connecting elements subsequently disengaged from each other, whereby 60
said other end of said linkage is pivotally connected to said dipper stick structure and disconnected from said boom structure.
7. The apparatus of claim 6 in which said linkage comprises a power operated linkage of 70

- adjustable length being adapted to swing said tool structure about said third horizontal axis as a result of alteration in its length;
- said second power means comprises a power operated actuating arm of adjustable length; and wherein the disposition of said boom structure, said dipper stick structure, and said linkage with respect to each other so that said first and fourth pivotal connecting elements may be operatively engaged is accomplished by the adjustment of said linkage and said second power means to predetermined lengths.
8. The apparatus of claim 7 in which said linkage and said second power means both comprise double-acting hydraulic cylinders; 80
said predetermined length of said linkage comprises its shortest length with its hydraulic cylinder fully retracted; and
said predetermined length of said second power means comprises its longest length with its hydraulic cylinder fully extended.
9. An excavating apparatus comprising the combination of:
support means;
a boom structure pivotally mounted upon said support means for motion about a first horizontal axis; 85
first power means operatively attached to said boom structure to swing said boom structure about said first horizontal axis;
a dipper stick structure pivotally mounted upon said bottom structure for motion about a second horizontal axis;
second power means operatively attached to said dipper stick structure to swing said dipper stick structure about said second horizontal axis;
a tool structure pivotally mounted upon said dipper stick structure for motion about a third horizontal axis;
a linkage having two ends, 90
one of said ends of said linkage being pivotally connected to said tool structure at a point spaced from said third horizontal axis, said linkage being provided with first and second bores adjacent the other of said ends;
said boom structure being provided with a third bore spaced from second horizontal axis;
said dipper stick structure being provided with a fourth bore; 95
said first and fourth bores being axially aligned and having a pin inserted therethrough, whereby said other end of said linkage is pivotally connected to said dipper stick structure;
said boom structure, said dipper stick structure, and said linkage being adapted to be so disposed with respect to each other that said second and third bores are axially aligned, whereby a pin may be inserted through them and said pin removed from said first and fourth bores, thereby converting said apparatus from one mode of tool motion to another.
10. The apparatus of claim 9 in which said linkage comprises a power operated linkage of adjustable length being adapted to swing said tool structure about said third horizontal axis as a result of alteration in its length; 100
said second power means comprises a power operated actuating arm of adjustable length; and wherein the disposition of said boom structure, said dipper stick structure, and said linkage with respect to each other so that said second and third bores are axially aligned is accomplished by the adjustment of said linkage and said second power means to predetermined lengths.
11. The apparatus of claim 10 in which said linkage and said second power means both comprise double-acting hydraulic cylinders;

said predetermined length of said linkage comprises its shortest length with its hydraulic cylinder fully retracted; and
said predetermined length of said second power means comprises its longest length with its hydraulic cylinder 5 fully extended.

12. An excavating apparatus comprising the combination of:

support means;
a boom structure pivotally mounted upon said support 10 means for motion about a first horizontal axis;
first power means operatively attached to said boom structure to swing said boom structure about said first horizontal axis;
a dipper stick structure pivotally mounted upon said boom structure for motion about a second horizontal axis; 15
second power means operatively attached to said dipper stick structure to swing said dipper stick structure about said second horizontal axis; 20
a tool structure pivotally mounted upon said dipper stick structure for motion about a third horizontal axis;
a linkage having two ends,
one of said ends of said linkage being pivotally 25 connected to said tool structure at a point spaced from said third horizontal axis,
said linkage being provided with first and second bores adjacent the other of said ends;
said boom structure being provided with a third bore 30 spaced from said second horizontal axis;
said dipper stick structure being provided with a fourth bore;
said second and third bores being axially aligned and having a pin inserted therethrough, whereby said other 35

end of said linkage is pivotally connected to said boom structure;
said boom structure, said dipper stick structure, and said linkage being adapted to be so disposed with respect to each other that said first and fourth bores are axially aligned, whereby a pin may be inserted through them and said pin removed from said second and third bores, thereby converting said apparatus from one mode of tool motion to another.

13. The apparatus of claim 12 in which
said linkage comprises a power operated linkage of adjustable length being adapted to swing said tool structure about said third horizontal axis as a result of alteration in its length;
said second power means comprises a power operated actuating arm of adjustable length; and
wherein the disposition of said boom structure, said dipper stick structure, and said linkage with respect to each other so that said first and fourth bores are axially aligned is accomplished by the adjustment of said linkage and said second power means to predetermined lengths.
14. The apparatus of claim 13 in which
said linkage and said second power means both comprise double-acting hydraulic cylinders;
said predetermined length of said linkage comprises its shortest length with its hydraulic cylinder fully retracted; and
said predetermined length of said second power means comprises its longest length with its hydraulic cylinder fully extended.
